J. N. GEORGE, OF BOSTON, AND JACOB R. SANBORN, OF WALTHAM,
MASSACHUSETTS.

Letters Patent No. 70,194, dated October 29, 1867.

IMPROVEMENT IN HAIR-BRUSHES.

The Schedule referred to in these Letters Patent and making part of the same.

TO ALL WHOM IT MAY CONCERN:

Be it known that we, J. N. GEORGE, of Boston, in the county of Suffolk, and J. R. SANBORN, of Waltham, in the county of Middlesex, all of the Commonwealth of Massachusetts, have invented a new and useful Improvement in Hair-Brushes, of which the following is a full, clear, and exact description, reference being had to the accompanying drawing, making a part of this specification, and representing a hair-brush, embodying our improvement.

The object of our invention is to combine in one instrument a hair-brush and a means for oiling or dressing the hair, and the invention consists of a hair-brush mainly of ordinary construction, having arranged in the central portion of the brush a piece of sponge- or other absorbent material which may be supplied with oil or other dressing for the hair, and thus dispense with the necessity of using two separate brushes for applying a dressing and for brushing the hair.

The drawing represents a hair-brush, A being the back, and B the bristles or hairs attached in the usual manner. In the central portion of the brush, instead of bristles or hairs, is attached, in any suitable manner, a piece of sponge, C. Instead of the sponge, layers of cotton or other absorbent material may be used, and attached in any convenient manner. The said sponge or absorbent material is designed to be supplied with oil or other dressing when used for the hair or scalp. It may also be used as a flesh-brush, for rubbing any part of the body. When the bristles or hair, of which the brush is composed, are of considerable length, a block or other substance should be interposed between the sponge and the back of the brush in order to prevent too great a quantity of oil or other dressing being absorbed by the sponge. When used for oiling the hair, the sponge should not be over half an inch in thickness, so as to allow the oil to be all pressed out, which would not be so well accomplished if the sponge is too thick, and the bristles long and hard.

It may be made with long, stiff bristles, and raised sponge for brushing and oiling the hair, or with short, soft bristles or hairs, with the sponge or other absorbent material in the centre for oiling, washing, or cleansing the hair and scalp, or the skin.

Having thus described our invention, what we claim as new, and desire to secure by Letters Patent, is—
The combination with a hair-brush of a sponge, C, or equivalent absorbent material, substantially as and for the purpose specified.

In testimony whereof we have signed our names to this specification in the presence of two subscribing witnesses.

J. N. GEORGE,
J. R. SANBORN.
